UNIT DISPENSING DEVICE

Frank G. Steiner, Chicago, Ill., assignor to
 Steiner Sales Company, Salt Lake City, Utah,
 a corporation of Utah

Application September 30, 1935, Serial No. 42,897

8 Claims. (Cl. 164—84.5)

This invention relates generally to improvements in unit dispensing cabinets particularly adapted for dispensing paper units, including paper drying units.

5 An important feature of the invention relates to a type of apparatus in which friction feeding is accomplished by means of the finger or fingers pressing the paper against a backing plate and moving it therealong to accessible position, either alone or in combination with severing, by pulling on a length of paper which has been thus brought to an accessible position.

Another important object of the invention is to combine with a finger-feed type of apparatus 15 in which there is pressure of the paper against a plate during feeding, means frictionally operated by the fed paper for limiting the degree of withdrawal of the paper either alone or in combination with means acting thereafter for preventing further feed for a predetermined time period. The control of limit-feeding or of limit-feeding with timing, by means of finger friction feed of paper along a backing plate is believed to be new in this art.

25 Features of the invention include: finger feed of the paper across a plate to an accessible position and severing by pulling; down-stroke feeding against and across a plate, and up-pull severing; means frictionally controlled by the paper 30 as it is finger-fed along the plate for limiting the degree of feed; the finger feed against the plate and the use of a roll frictionally controlled by the paper, as it is finger-fed, for limiting the degree of feed; the use of a backing plate and 35 door as guiding means; the placement of the tear-off knife on the door; the use of the tear-off knife as means cooperating with the backing plate to form an exit or delivery opening for the cabinet; the arrangement of the tear-off blade 40 and exit opening at the bottom of the cabinet; the positioning of the blade on the door so that severing is obtained by up-pull; the use of plates to form a paper guide and the specific manner of hinging the plates; a simple relatively inexpensive device; and all details of construction, along 45 with the broader ideas of means inherent in the disclosure.

Objects, features and advantages of the invention will be set forth in the description of the 50 drawings forming a part of this application, and in said drawings

Figure 1 is a vertical transverse section taken approximately on line 4—4 of Figure 2;

Figure 2 is a front elevation with parts broken 55 away;

Figure 3 is a plan section taken approximately on line 3—3 of Figure 2;

Figure 4 is a vertical section approximately on line 4—4 of Figure 2 showing the stop mechanism and timer as at the beginning of timing; 5

Figure 5 is a side elevation partly broken away showing the position of the stop mechanism and timer as at the end of timing;

Figure 6 is a vertical section similar to Figure 1 but showing a modification; and 10

Figure 7 is a view of the form of Figure 6 showing the stop and timer mechanism, as at the beginning of timing.

In the drawings, see Figure 1, numeral 1 generally indicates the outer casing of a cabinet 15 having a sheet metal plate as a door 2 hinged at the top as at 3, and having an elongated opening 4 through which the fingers pass to engage the paper for friction feeding. At the bottom and inner side of the door is arranged a tear-off 20 blade 5 having a serrated tear-off edge 6. Spaced inwardly from the door and hinged at the bottom to the cabinet as at 8, is a plate 10 herein called a backing plate against which the paper is finger-pressed and finger-moved to an accessible 25 position.

The bottom portion of the plate 10 and the tear-off blade 5 define a transverse delivery opening or slot which, in this instance, is located at the bottom of the cabinet. The upper edge of 30 the plate is bent and rounded as at 11. Referring to Figure 3: Inward movement of the plate is limited by means of the front edge of a vertical partition 14 and by the front edge of a bracket plate 15, these two elements also forming bearing or 35 journal plates for a friction roll 16 having a shaft 17. The backing plate is locked against outward movement, see Figures 2 and 3, by means of slide latches 20 engaged with in-turned portions 21 of the sides 22 of the cabinet. The door is held 40 closed by means of button latches indicated at 25 having locking elements also cooperating with openings (not shown) in the in-turned portions 21.

45 Referring again to Figure 1: There is a gravity-operating pinch roll 26 cooperable with the roll 16. The paper supply roll is indicated at 27 and the paper 28 is passed from the forward side of the roll upwardly over the roll 16 around the pinch roll 26 and downwardly against the rounded portion 11 of the backing plate downwardly across the outer face of the plate, generally to the position shown in dotted lines, after which the paper 50 is generally torn off. The pinch roll has a shaft 30 journaled in suitably shaped slots 31, carried 55

by the plate 14 and bracket 15. This slot construction is old in the art, and permits raising of the roll, and securing of the same in raised position to facilitate threading-through of the paper.

The roll 16 constitutes means frictionally controlled by the paper as it is finger-fed along the plate for controlling means to limit the degree of feed. This limiting means structure per se is not claimed herein, but I believe it new to control such a means alone or with timing means, by the friction action of paper, which is finger-fed across a plate. Referring to Figure 4: There is arranged at the outer side of the plate 14 and fixed to the roll shaft 17 a stop arm 35. A stop slide 36 is suitably slidably arranged in a slot 37 of the plate 14 and this slide is operably connected as at 38 with the stem 39 of a dashpot type of timer, the barrel of which is indicated at 40. The timer per se is not claimed. In order to control the arm and slide for the purposes herein, the same are connected by a link 42 slotted lengthwise at 43. A pivot screw 44 passes through the slot and connects with the arm to form a sliding connection. The opposite end of the link is pivotally connected with a projection 46 of the stop slide 36 whereon it is held by split pin 47.

With the parts positioned as in Figure 5, feeding can be accomplished and during finger feeding the paper, acting frictionally on the roll 16, moves the arm in counter-clockwise direction. After the arm has moved to the right across the top of the slide to clear it, the link is acted upon to raise the slide to the position shown in Figure 4, thus setting the timer. One complete rotation of the roll, brings the stop arm and stop slide to stop position with the timer set, and released to begin timing. This mechanism per se is not claimed herein.

As long as the slide 36 occupies the position shown in Figure 4, no feeding of the paper can take place because of the frictional relation of the paper with the roll 16. A ratchet wheel 50 and pawl 51 prevent improper rotation of the roll 16. A back-off mechanism is also provided to assure free motion of the slide 36 under control of the timer. This consists of a cam 52 on roll 16, and a roller 53 carried by an arm 54 pivoted as at 55 to the plate 14 and spring pressed to the position shown to engage the roller 53 with a cam projection 56. After the arm 35 strikes the slide 36 as it does to limit the feed, the roller acting on the projection 56 rotates the roll slightly in clockwise direction to back the lower end of the arm away from the slide 36 to the slightly spaced position shown, whereby downward movement of the plate is not interfered with by any frictional engagement of the arm therewith.

In Figure 6, a modification is shown in which the gravity-acting pinch roll is replaced by a spring-pressed roll 62 acting against roll 60. The roll 62 has a shaft 63 supported in horizontal slots 64 respectively carried by the plate 14 and the bracket 15. Springs 66 engage the projecting ends of the shafts as shown in Figure 7. In this instance, the paper 28 is brought from the forward side of the roll 27 upwardly between the rolls 60 and 62 and then around roll 60 and downwardly across the rounded upper portion 11 of the backing plate 10, thence downwardly through the guide formed by backing plate and door.

The feed-limit and timing structures are substantially the same as in the first form, the only difference being that the rotation of the roll 60 for feeding is clockwise rather than counter-clockwise. The back-off mechanism is the same

as in the first form, the elements being merely positionally reversed because of the change in direction of rotation of the roll 60 over the roll 16.

Operation

5

In loading the cabinet, the door 2 is swung upwardly to lie on top of the cabinet, and the backing plate swung downwardly to the dotted position shown in Figure 1. The roll of paper is then introduced, and paper is passed upwardly between the rolls, thence downwardly over the upper end of the plate and downwardly through the guide and through the orifice formed by the backing plate and the tear-off knife, to an accessible position, after which the paper is generally torn off. 15

In using the device, the paper may be finger-fed sufficiently to bring it into view and to a position accessible for grasping, and then the accessible portion may be grasped and pulled to the limit as determined by the stop mechanism; or feeding out of the entire predetermined length may be accomplished by finger feeding. Preferably the user passes his finger or fingers through the slot 4, engages the paper and moves it downwardly as it lies upon the backing plate, to bring a sufficient length of paper into view for grasping. Then he grasps the paper and pulls it to the limit of feed after which he brings the paper upwardly to the dotted line position of Figure 1 and tears off along the toothed edge 6 by an upward-pulling motion. No more paper can now be fed until the slide has moved to its position in Figure 5.

I claim as my invention:

1. A paper dispensing apparatus comprising a cabinet having a plate forming a partial closure for the front of the cabinet, a door for the cabinet slightly spaced from the plate and having an elongated vertical slot through which the finger passes to press the paper against and feed it along the plate, tearoff means placed adjacent the bottom of the plate and door below which the paper is fed to assume tearoff relation, a measuring roll over which the paper passes from a supply roll, and a roll engaged with the measuring roll and from which the paper is led around the upper edge of the backing plate.

2. A paper dispensing apparatus comprising a cabinet having a plate, a door for the cabinet slightly spaced from the plate and having an elongated vertical slot through which the finger passes to press the paper against and feed it along the plate, tearoff means placed adjacent the bottom of the plate and door below which the paper is fed to assume tearoff relation, and a measuring roll upwardly to which the paper passes from a supply roll and from which the paper is led downwardly around the upper edge of the backing plate.

3. A paper dispensing apparatus comprising a cabinet having a plate forming a partial closure for its front and hinged thereto to swing downwardly to allow servicing of the cabinet, a door for the cabinet pivoted thereto to swing upwardly, said door being slightly spaced from the plate and having an elongated vertical slot through which the finger passes to press the paper against and feed it along the plate, tearoff means placed adjacent the bottom of the plate and door below which the paper is fed to assume tearoff relation, a measuring roll upwardly to which the paper passes from a supply roll, and a pinch roll for the measuring roll from which the paper is led slantingly downwardly around the upper edge of the plate.

4. A paper dispensing apparatus comprising a

75

cabinet having a plate, a door for the cabinet slightly spaced from the plate and having an elongated vertical slot through which the finger passes to press the paper against and feed it along the plate, tearoff means placed adjacent of the bottom of the plate and door below which the paper is fed to assume tearoff relation thereto, a measuring roll arranged near the top of the cabinet and upwardly and over which the paper passes from a supply roll which rests upon the bottom of the cabinet, and the paper passing downwardly from the roll around the upper edge of the backing plate.

5. A cabinet, having therein a plate against which the paper is pressed and slid to feed it, and a measuring roll from which the paper passes to the plate, whereby the roll is operated as the paper is slid.

6. A paper dispensing cabinet having a measuring roll operated by the paper, a plate receiving the paper from the roll and against which the paper is pressed and slid for feeding, and a pinch roll cooperating with the paper on the measuring roll, the paper being led over the pinch roll 25 thence to the plate.

7. A paper dispensing cabinet having a measuring roll operated by the paper, a first plate receiving the paper from the roll and against which the paper is pressed and slid for feeding, the paper being led upwardly over the roll and thereafter passing to and against the plate, said first plate being hinged at the bottom of the cabinet, a second plate hinged at the top of the cabinet and forming with said first plate a guide, the bottom of said last mentioned plate having a 10 blade against by which the paper can be torn off after being fed across the first mentioned plate by the finger of the user, the said second plate having a vertically elongated slot through which the finger is passed to press the paper 15 against the first plate and slide the paper.

8. A paper dispensing cabinet having a measuring means operated by the paper, a plate receiving the paper from said means and against which the paper is pressed and slid for feeding, the paper being led upwardly over the measuring means and thereafter passing against and around an upper smoothing edge of said plate, then against the face of the plate.

FRANK G. STEINER. 25
